LIPA POLINKOWSKY, OF HYDE PARK, LONDON, ENGLAND, ASSIGNOR TO WESTERN ELECTRIC COMPANY, INCORPORATED, OF NEW YORK, N. Y., A CORPORATION OF NEW YORK.

CALL-DISTRIBUTING SYSTEM.

1,340,979.

Specification of Letters Patent. Patented May 25, 1920.

Application filed July 16, 1918. Serial No. 245,222.

To all whom it may concern:

Be it known that I, LIPA POLINKOWSKY, a citizen of Russia, residing at 70 Westbourne Terrace, Hyde Park, London, W., England, have invented certain new and useful Improvements in Call-Distributing Systems, of which the following is a full, clear, concise, and exact description.

This invention relates to call distributing systems, and more particularly to call distributing systems for semi-automatic telephone switching systems, and provides that in a system where normally calls may be extended only to idle operators, apportioning 15 means is brought into action upon the initiation of calls which find no idle operator accessible thereto to extend such calls to an operator, whether busy or idle, and prevent the holding up of calls of the existence of 20 which the operators or supervisors of the exchange are in ignorance.

A particular feature of the invention involves the busy guard on an operator's position being removed immediately upon the 25 incoming of a call which finds no operator's position accessible thereto.

A further feature of the invention provides for automatic discrimination with regard to the operators who will be accessible 30 to such call, one form of the invention providing that, as a preliminary, only such operators will be rendered accessible to such call as have at that time but a single call extended thereto which has not as yet 35 reached a predetermined stage in its extension.

A still further feature of the invention provides that under certain conditions, a further disabling of the busy guard will take 40 place on the various operators' positions, and, in accordance with one form of the invention, this disablement of the busy guard, which results in the apportioning of an additional call to such positions, takes place 45 regardless of the number of calls at that time connected to the operator's position, which have not as yet received attention from such operator.

A further feature of the invention, relating 50 to the feature above mentioned, involves the apportioning apparatus, that is, the apparatus by which the busy guard upon the

various operators' positions is disabled, operating in a cycle and continuing to operate apportioning a further call to each operator's position so long as the condition which initiated its operation maintains. 55

Still another feature of the invention relates to an improved arrangement of circuits and apparatus for the timing of the period 60 for which the busy guard will be maintained upon an operator's position and in a specific form provides for a form of timing apparatus which is readily adapted to be rendered ineffective as may be required when 65 the apportioning means referred to has been set in operation.

Still another feature of the invention provides for the specific timing arrangement whereby the apportioning apparatus operates 70 first to apportion calls to such operators as are best in the position to handle such calls, that is, in accordance with the discriminating function of the apportioning apparatus above referred to, and, subsequently, after a 75 definite delay, causing the apportioning of a call to all of the operators' positions, provided the condition which has brought about the operation of the apportioning of the apparatus is still maintained. 80

Further features of the invention will sufficiently appear from the description of the embodiment thereof.

The accompanying figure of the drawing shows one embodiment of the invention. 85

A description of the invention, as disclosed in the drawing, will be best given by a description of the operation and the circuits and apparatus therein shown.

It is assumed that a call is initiated upon 90 the line 10 in the usual manner, causing the energizing of the line relay 11 and the consequent energization of the usual pilot relay 12, which initiates the operation of the idle first line finders having access to the line 10 95 and places the testing potential upon the test contact 13 individual to such line in such first line finders. The first line finders which comprise the usual power magnet 14, test relays 15 and 17, interrupter 19 and holding 100 magnet 20, operate to select and one of them seizes the calling line 10 in the usual manner, the energization of the test relay 15 in so doing placing selectable potential upon the

test terminal 21 of the trunk line associated with such first line finder in the second line finders having access thereto and also causing the energization of the pilot relay 22 to cause the initiation of the operation of the idle second line finders having access to this trunk line in the well known manner. These second line finders, which each comprise the usual power magnet 24, test relays 25 and 27 and interrupter 26, are set in motion, if idle, by the energization of the relays 23 individual respectively thereto by the energization of the pilot relay 22. Whether or not the relay 23 of any given second line finder will be energized depends (1) on whether such second line finder and the connecting circuit individual thereto are already in use, that is, whether the sequence switch 50 associated with such circuit is out of its normal position and (2) on whether the timed busy guard on this operator's position is effective or not, that is, whether the sequence switch contact 133 is open to render such busy guard effective or is closed to allow further calls to come in on such operator's position.

It should be noted that on the drawings the sequence switch contacts shown in any area circumscribed by dotted lines form a part of and are operated by the sequence switch indicated within such area. These sequence switches are of well known and usual construction and the operation of their contacts is in the usual manner. Furthermore the indication on the drawings of the positions in which such sequence switch contacts are opened and closed is in the manner well known in the published art and need not be described in detail herein.

Furthermore the heavy dotted lines upon the drawings divide apparatus individual to different operators' positions, that is, the apparatus and circuits shown to the left of the drawing above the dot and dash line is individual to one operator's position. The apparatus between the first and second heavy dotted lines such as the relays 157 and 158 are individual to a second operator's position and so on, the third and fourth operator's position being merely indicated.

The apparatus on the lower part of the drawing and separated from the other apparatus by the dot and dash line is common to a plurality of operators' positions and may be, if desired, common to the entire exchange. Its function will be made clear hereinafter.

Assuming that the second line finder indicated and its connecting circuit are idle and that the operator on whose position such connecting circuit appears is also idle, the energization of the pilot relay 22 causes the energization of the guard relay 30 to prevent the illumination of the guard lamp 31, such guard relay and guard lamp being common to all of the second line finders having ac-

cess to the trunk line of the first line finder taken for use and also causes the energization of the relay 23. This causes the second line finder to be started in motion to select and it will be presumed this second line finder seizes the trunk line taken for use, in which operation the test relay 27 is energized (1) to cause the stopping of the second line finder in the usual manner, (2) to move the sequence switch 50 out of its first 70 into its fourth position, and (3) to cause the energization of the relay 28. In the fourth position of the sequence switch 50, the sequence switch contacts 55, 56 and 57 being closed, the selection and seizure of an idle 75 registering and controlling equipment of this operator's position will take place through the operation of the equipment selecting sequence switch 90 in the well known manner, such, for instance, as described in United States patent to L. Polinkowsky, No. 1,160,447, of November 16, 1915. This sequence switch 90 will be energized by current flowing over the relays 107 and 108 in parallel, sequence switch contact 57, back 80 contact and armature of the relay 27 which was deenergized when the sequence switch 50 left its third position and front contact and armature of the relay 23 which relay is maintained energized in the fourth and 85 fifth positions of sequence switch 50 by any suitable means, as for example by a circuit including sequence switch contact 56 and the back contact and armature of the supervisory relay 29.

The relays 107 and 108 which, as are indicated, are common to this operator's position are so adjusted that the relay 107 alone will be energized if but a single equipment searching sequence switch 90 is included in 105 circuit therewith, whereas both said relay 107 and the relay 108 will be energized if two or more of such switches 90 are at the same time in circuit therewith, that is, if but a single call extended to a connecting 110 circuit on this operator's position has not as yet found and seized an idle registering and controlling equipment of this operator the relay 107 alone will be energized, whereas, if a plurality of calls extended to the connecting circuits of this operator's position have not as yet found and seized idle equipments of this operator both of said relays 107 and 108 are energized.

Meanwhile upon the energization of the 120 relay 28, as above described, the relay 92 was energized closing over its right armature a circuit including the sequence switch contact 102 to move the sequence switch 100 out of its first into its third position. The relay 125 92 closes at the same time over its left armature a circuit including the sequence switch contact 122 top to drive the sequence switch 120 out of its first and into its sixth position.

As the sequence switch 120 came into its 130

second position it closed a circuit including the sequence switch contacts 123 top and 132 top to drive the sequence switch 130 out of its first and into its sixth position. In 5 leaving its first position the sequence switch 130 opens the sequence switch contact 133 of which there is one of such sequence switch contacts individual to all of the connecting circuits upon this operator's position opening 10 the starting or pilot wire of all of the second line finders associated with connecting circuits upon this operator's position and rendering such operator's position busy and inaccessible to further incoming calls 15 until such sequence switch 130 comes again into its first or normal position in which such sequence switch contacts 133 are again closed.

In the normal course such sequence switch 20 130 would be restored to its normal position when the sequence switch 100 returns to its first or normal position in which position the sequence switch contact 104 bottom is closed to drive the sequence switch 120 out of its 25 sixth into its first or normal position, the sequence switch contact 122 bottom being closed at this time, the restoration of the sequence switch 120 to its normal position closing a circuit through the sequence switch contacts 123 bottom and 132 bottom to drive the sequence switch 130 out of its sixth position to come to rest in its first or normal position.

Assuming that the incoming call in question 30 has immediately been connected by the sequence switch 90 to an idle registering and controlling equipment, test relays 25 and 27 having been operated in the well known manner, the circuit for the switch 90 and the relays 107 and 108 is open at the 35 back contact of the test relay 27 and the sequence switch 50 is driven out of its fourth and fifth position and the call progresses from this point on in the well known manner which need not be described herein. Therefore, immediately that the sequence switch 100 comes into its sixth position the relay 107 being deenergized a circuit is established over the armature and back contact 40 of such relay and the sequence switch contact 106 to initiate the movement of the sequence switch 100 to its normal position and the consequent restoration of the sequence switch 130 to its normal position, as has been described, to remove the timed busy guard control by the sequence switch contacts 133 from this operator's position. The time interval for 45 which such busy guard is maintained will obviously depend upon the time required to bring (1) the sequence switch 100 into its normal position, (2) to bring the sequence switch 120 into its normal position, and (3) the time required to bring sequence switch 50 130 into its normal position after the se-

quence switch 120 has reached its normal position.

As shown, the sequence switch 100 on leaving its first position stops in its third position in which position it will remain until as the interrupter 110 revolves the relay 109 is energized to drive the sequence switch 100 out of its third position and into its fourth position over a circuit including the armature and front contact of such relay. 75

The interrupter 110, which may be common to the exchange, is arranged to energize the relay 109 for but a brief period, so that the circuit for energizing the relay 109 when the sequence switch 100 is in its third position will be opened before such circuit is again closed at the sequence switch contact 105 bottom in the fourth position. The sequence switch 100 will remain in its fourth position until the interrupter 110 has again 85 closed the circuit of the relay 109 when it will be moved into its fifth position where it will similarly remain until, due to a further energization of the relay 109, it is driven into its sixth position, when it will 90 be controlled by the deenergized condition of the relay 107 as has been hereinbefore described.

Let it now be assumed that upon the energization of the test relay 15 and the consequent energization of the pilot relay 22 in the extension of a call all of the second line finders having access to the trunk line extending from the first line finder with which such relay 15 is associated were inaccessible 100 due either to the fact that such second line finders were actually in use or that the operators upon whose position the connecting circuits associated therewith appear were busy and the sequence switch contacts 133 105 associated respectively with such second line finders were opened.

The preferred distribution of connecting circuits upon operators' positions is well known and will be but briefly described. 110 The second line finders are arranged in groups, each group having access to a group of trunk lines leading to a group of first line finders. Each group of second line finders is divided into a plurality of such 115 groups, preferably of three or more each, such sub-groups severally appearing upon a plurality of operators' positions, so that each operator accessible over a plurality of sub-groups of second line finders will be accessible from a large number of first line finders and to a very large number of calling lines. 120

In the case last assumed on the various busy operators' positions one or both of the 125 relays 107 and 108 may be energized, such energization preventing the restoration of the sequence switch 130 to normal even though the sequence switch 100 has come into its sixth position. 130

The extension of the call that has been extended to the first line finder shown is now obviously impossible over the second line finders having access thereto which are already in use. Such extension is, however, possible over second line finders having access thereto which are not in use but are rendered busy by the fact that the sequence switch contact 133 respectively individual thereto is open. When, therefore, the relay 22 is energized, since no circuit exists from the front contact of the armature thereof to any of the relays 23, the sequence switch contact 52 or the sequence switch contact 133 of all such circuits to which the armature of the relay 22 is common being open the relay 30 is not energized. The guard lamp 31 is consequently lighted and the slow operating relay 33 individual to this group of second line finders starting circuits energized. This relay 33, or the relay 83 equivalent thereto which is individual to some other group of starting circuits indicated on the drawings by the pilot relay 82, guard relay 80 and guard lamp 81, controls the starting circuit for the apparatus common to a plurality of the operators' positions or to the exchange, shown below the dot and dash line upon the drawing, that is, whenever an incoming call having been connected to by a first line finder finds all of the second line finders by which it may be extended disabled the apportioning apparatus common to the plurality of operators' positions is set in motion to apportion one additional call to each of such operators' positions of which the relay 107, 157, etc., alone is energized and to apportion still further calls from time to time thereafter as will be hereinafter described.

The energization of the relay 33 or 83 closes a circuit over the sequence switch contact 202 to energize the relay 211. By the attraction of its left hand armature this relay closes for itself a locking circuit independent of the sequence switch contact 202.

By the attraction of its right hand armature such relay causes the energization of the relay 212 and of the relays 111, 191, etc. The relays 111 and 191 each serve two operators' positions in the manner clearly indicated on the drawings and are all simultaneously energized upon the energization of the relay 211. On the operator's position shown in the left hand corner of the drawing, it will be assumed that but a single connecting circuit is still unconnected to a registering and controlling equipment and that consequently the relay 108 is not at this time energized. On this position, as on all of the other positions of the plurality to which the apportioning apparatus is common in which this condition maintains, the energization of the relay 111 or its equivalent relay closes a circuit to ground in sub-

stitution for the circuit usually closed over the back contact and armature of the relays 107, 157, etc., and the sequence switch 100 is consequently moved from its sixth position with the consequent operation of the sequence switches 120 and 130, which closes the sequence switch contacts 133 upon such positions and permits idle second line finders thereon having access to the first line finder to which the call in question has been extended, to search for and seize the trunk line extending to such first line finder. As a result of this operation it will be obvious that each operator's position upon which the condition described maintains may have connected thereto one further call.

The energization of the relay 212 as described prepares a circuit to be closed by the interrupter 216 to energize the relay 215. When such relay is energized, it closes the circuit through the left winding of the differential relay 213 direct to battery and through the right winding of such relay 213, the back contact and armature of such relay and sequence switch 200 to battery. The relay 213 is not energized but the sequence switch 200 is driven out of its first position and into its second position. After leaving its first position, the sequence switch 200 closes its local contact 201 in the well known manner thereby short circuiting the right winding of the relay 213 and causing such relay to energize. This movement of the sequence switch 200 also causes the energization of the relay 214 which will maintain the relay 213 energized until the sequence switch 200 is approaching its second position, even though the original energizing circuit for the relay 213 over the armature and front contact of the relay 215 has been broken, due to the interruption of the circuit of such relay in the further movement of the interrupter 216. So long as the relay 211 and consequently the relay 212 are maintained energized, the sequence switch 200 will remain in its second position until the circuit for the relay 215 is again closed by the interrupter 216 when sequence switch 200 will move into its third position and will again move out of its third position to be restored to its normal position in the same manner, provided, of course, the relays 211 and 212 are still energized. The energization of these relays, however, depends upon the continued energization of the relay 33 or 83 the energization of which in turn depends upon the continued existence of the condition that a calling line connected to a first line finder finds no second line finder having access to such first line finder in condition to search for and seize the trunk line leading thereto.

It will first be assumed that the apportioning apparatus having operated to apportion a further call to each operator's po-

sition on which but a single call is already awaiting attention, the further incoming call which has brought about this operation is connected to by one of the idle second line finders having access thereto before the sequence switch 200 leaves its third position, and further that no other incoming calls extended to first line finders now find no second line finders available to be connected thereto. In this event, either the guard relay 30 is energized or the pilot relay 22 is deenergized and either condition causes the opening of the circuit which has lighted the guard lamp 31 and energized the slow operating relay 33. The relay 33 having fallen off, the relay 211 is deenergized and consequently the relays 111, 191 and 212 are immediately deenergized. The retraction of the right armature of the relay 211 closes a circuit over the sequence switch contact 203 to drive the sequence switch 200 directly back to its normal position and this will take place whether the sequence switch is in its second or third position. The deenergization of relays 111 and 191 has rendered without effect the closure of the sequence switch contacts 204, 205, 206 and 207 in this restoring movement of the sequence switch 200.

It should be noted that the relays 33 and 83 are slow to operate. The purpose of this is to prevent a temporary energization of these relays respectively while the relays 30 and 80 are attracting their armatures in the normal operation thereof. Each time, however, that a relay 33 or 83 is energized a further incoming call is apportioned to each of the operators having but a single call extended to a connecting circuit on her position to which a registering and controlling equipment has not as yet been connected.

Assuming, on the other hand, that, when the apportioning apparatus has been started in operation and after the time interval necessary for such apportioning apparatus to drive the sequence switch thereof out of its third position, the relays 211 and 33 or 83 are still energized indicating that, in spite of the apportioning of calls as hereinbefore described and the timed delay due to the cycle of operations between the interrupter 216 and the sequence switch 200, as has been described, there are still calls which have been extended to first line finder switches that find no second line finder switches available to further extend them. The sequence switch 200 in passing through its fourth to sixth positions in returning to normal closes the sequence switch contacts 204, 205, 206 and 207. At this time, due to the energization of the relay 211, the relays 111 and 191 are energized on each operator's position (according to the assumption each operator is busy and the sequence switch 100 thereof is either in or coming in to its sixth

position) a circuit is established from sequence switch 100 through sequence switch contact 106, sequence switch contact 204 and front contact and armature of relay 111, and such sequence switch 100 is restored to its normal condition removing the busy guard from this operator's position by the closure of the sequence switch contacts 133 in the now well understood manner, in spite of the fact that one or both of the relays 107 and 108 of such operator's position are energized. It will, therefore, be seen that under the condition assumed a further call may be apportioned to each operator's position regardless of the number of calls already extended to her position which are still awaiting attention. Each such additional apportioned call, when it has been extended to a connecting circuit on an operator's position, causes the energization of the relays 27, 28 and 92 individual to such connecting circuit and causes the sequence switches 100, 120 and 130 to move from their normal positions to reestablish the busy guard, as has been hereinbefore described. If, when the sequence switch 200 returns to its normal position, all the calls extended to first line finders have available second line finders to extend them, the relay 211 will be found deenergized and the sequence switch 200 will come to rest in its normal position. If, on the other hand, due to some sudden influx of calls, the condition that second line finders are not available to extend certain calls is maintained, when the sequence switch 200 reaches its normal condition, it will continue in operation precisely as before described. Each time it passes through the fourth to sixth positions of its cycle it disables the timed busy guard on each operator's position to apportion another incoming call to such operator's position.

What is claimed is:

1. A call-distributing system comprising calling lines, operators' positions, means for normally extending a call only to idle operators, and means operable upon the initiation of calls that fail to find an idle operator for extending such calls to busy operators.

2. A call-distributing system comprising calling lines, operators' positions, means for normally extending calls only to idle operators' positions, means for rendering said positions busy to other calls, and means operable upon the initiation of calls when all positions are busy for removing the busy condition to permit such calls to be extended to busy operators' positions.

3. A call-distributing system comprising calling lines, operators' positions, means for normally extending calls only to idle operators' positions, means for rendering said positions busy to other calls, and means operable upon the initiation of calls when all positions are busy for removing the busy

condition from certain of said operators' positions to permit such calls to be extended thereto.

4. A call-distributing system comprising 5 calling lines, operators' positions, means for normally extending calls only to idle operators' positions, means for rendering said positions busy to other calls, and means operable upon the initiation of calls when all 10 positions are busy for removing the busy condition to permit such calls to be extended only to such operators' positions as have not more than a predetermined number of calls extended thereto.

5. A call-distributing system comprising 15 calling lines, operators' positions, means for normally extending calls only to idle operators' positions, means for rendering said positions busy to other calls, and means operable upon the initiation of calls when 20 all positions are busy for removing the busy condition to permit such calls to be extended to such operators' positions as have at the time but a single call extended thereto which has not yet reached a predetermined stage in its extension.

6. A call-distributing system comprising 30 calling lines, operators' positions, means for normally extending calls only to idle operators' positions, means for rendering said positions busy to other calls, means operable upon the initiation of calls when all positions are busy for removing the busy condition to permit such calls to be extended 35 to certain of said busy positions, and further means for removing the busy condition to permit calls to be extended to all of said busy operator's positions.

7. A call-distributing system comprising 40 calling lines, operators' positions, means for normally extending calls only to idle operators' positions, means for rendering said positions busy to other calls, means operable upon the initiation of calls when all 45 positions are busy for removing the busy condition to permit such calls to be extended only to such operators' positions as have a predetermined number of calls extended thereto, and means operable upon 50 the initiation of further calls for removing the busy condition to permit such further calls to be extended to any of said operators' positions regardless of the number of calls that has previously been extended 55 thereto.

8. A call-distributing system comprising 60 calling lines, operators' positions, means for normally extending calls only to idle operators' positions, means for rendering said positions busy to other calls, means operable upon the initiation of calls when all 65 positions are busy for removing the busy condition to permit such calls to be extended only to certain of said operators'

positions, and means responsive to the initiation of further calls for removing the busy condition to permit such further calls to be extended to any of said operators' positions, said last named means being arranged to operate in cycles and to remain 70 effective as long as there exists any unextended calls.

9. A call-distributing system comprising 75 calling lines, operators' positions, means for normally extending calls only to idle operators' positions, means for rendering said positions busy to other calls, and timing means responsive to the initiation of calls when all positions are busy for removing the busy condition to permit such calls to be 80 extended to busy operators' positions.

10. A call-distributing system comprising 85 calling lines, operators' positions, means for normally extending calls only to idle operators' positions, means for rendering said 90 positions busy to other calls, timing means responsive to the initiation of calls when all positions are busy for removing the busy condition to permit such calls to be extended to certain operators' positions, and means responsive to said timing means for removing the busy condition to permit calls to be extended to all of said operators' positions.

11. A call-distributing system comprising 95 calling lines, operators' positions, means for normally extending calls only to idle operators' positions, means for rendering each position temporarily busy after a call is extended thereto, means for maintaining 100 said busy condition at each of said positions when a definite number of calls has been extended to such positions, and means operable upon the initiation of calls when all 105 positions are busy for removing the busy condition to permit such calls to be extended to busy operators' positions.

12. A call-distributing system comprising 110 calling lines, operators' positions, means for normally extending calls only to idle operators' positions, means for rendering each position temporarily busy after a call is extended thereto, means for maintaining 115 said busy condition at each of said positions when a definite number of calls has been extended to such positions, means operable upon the initiation of calls when all positions are busy for removing the busy condition to permit such calls to be extended only to certain operators' positions, 120 and means responsive to the initiation of further calls for removing the busy condition to permit such calls to be extended to all said operators' positions.

In witness whereof, I hereunto subscribe 125 my name this 6th day of May A. D., 1918.

LIPA POLINKOWSKY.
